UNITED STATES PATENT OFFICE.

AGAMEMNON COUNAS, OF PARIS, FRANCE.

ELECTRICAL FURNACE FOR TREATING ORES.

Application filed August 21, 1920. Serial No. 405,127.

To all whom it may concern:

Be it known that I, AGAMEMNON COUNAS, a subject of the King of Greece, and residing in Paris, France, 133 Boulevard Saint-5 Michel, have invented certain new and useful Improvements in and Relating to Electrical Furnaces for Treating Ores, of which the following is a complete specification.

This invention relates to an electric furnace for treating in the electric furnace, ores, such as lead, zinc, copper or other ores.

The treatment of the ores, particularly the lead ores is carried out in the majority of the processes at present in use, in air blast 15 water-jackets, by carrying out first of all a preliminary roasting, which even in the majority of cases has to be effected in such a way that the lead ore treated in the furnace only retains a very small quantity (2 20 to 3 per cent for example) of sulphur, in order to obviate the formation of matte of lead retaining a large quantity of lead. The melting of the ore is effected after this double roasting in furnaces other than electric 25 furnaces, on account of the excessively high temperature given by the latter, which would occasion the volatilization of the lead.

One object of the invention is to enable the complete treatment of the ores to be carried out in one and the same furnace, without it being necessary to subject them to a preliminary roasting and enables both the temperature of the furnace and the position of the zone of maximum temperature to be 35 regulated so as to render the fusion of the metals possible while only permitting of the volatilization thereof when that is advantageous to the operation.

In the accompanying drawing, various 40 constructional forms of an electric furnace are illustrated.

Fig. 1 is an elevation of the furnace, half in section.

Fig. 2 is a sectional plan thereof through 45 the hopper and through the upper part of the heating chamber of the furnace.

Fig. 3 shows a modification.

This furnace comprises a lower part or vat 50 a, surmounted by a charging hopper b of convenient height, having a breadth less than that of the vat a and extending throughout the entire length of the furnace as shown more particularly in Figure 2.

The part c of the hearth of the furnace is 55 located directly underneath the hopper b and consists of a substance which is a con-

ductor of electricity such as retort carbon for instance, forming the terminal for the return of the current, the current being admitted through electrodes d, e each of which 60 consists of a block of material such as carbon extending into the vat a inside a water jacket f and mounted on a rod g supported by a suitable frame h. The upper end i of each rod g is screw-threaded as shown in 65 Figure 1, and supports a nut j the periphery of which has teeth in gear with a pinion k provided with a hand operated device, enabling the extent to which the electrodes project into the interior of the vat a to be 70 varied at will. In this way it is possible to regulate the distance of each of the electrodes d, e from the central return terminal c, so as to regulate at will the temperature of the furnace and the position of the zone 75 of fusion.

In consequence of the particular arrangement of the charging hopper b the vapours that are liberated during the treatment of lead ores inside the vat a come into contact 80 with the material to be treated contained in the hopper b and condense upon contact with the said material, owing to the arrangement of the medial return electrode c, which concentrates the heat towards the middle of the 85 furnace and facilitates the rise of the fumes in the hopper.

As shown in Figure 2, the electrodes d, e may be single or multiple, each of them admitting or being formed of any number of 90 elements distributed along the length of the furnace, so that in this way it is possible to vary at will the power of the furnace by suitably increasing the number of electrodes, the length of the furnace varying at the 95 same time and in the same direction.

The operation is as follows: The roasted ores are introduced into the vat a by causing them to enter the hopper b, and then the current is passed through the electrodes d, e, 100 thereby producing in the interior of the vat an appropriate temperature, concentrated on the central part c of the said vat so that vapours liberated come and condense immediately upon contact with the cold part of 105 the charge which is still contained in the hopper b. In consequence of this arrangement losses by volatilization are almost completely eliminated.

The arrangement described makes it possible, by suitably varying the position of the electrodes d, e in relation to one another and

to the return terminal *c*, to regulate the position of the arc, and consequently to determine with precision the temperature of working of the furnace as well as the location where the temperature is to be highest.

For the case of the utilization of the furnace according to the invention for the concentration of ores poor in zinc, oxydized or sulphurous, a slightly different constructional form of the furnace is used, which is shown in Figure 3.

In this constructional form the hopper has at its base a suitable number of apertures *m*, which may be distributed over the four faces of the hopper, or only over two opposite faces, each of the apertures being adapted to receive a plug, preferably of a refractory material, not shown. In this case a fan or other suitable suction device is arranged outside the hopper, exerting suction in the said hopper through a large aperture *n* for example arranged at one of the ends. The hopper is kept completely free and the speed of working of the fan is so adjusted as to pass through the apertures *m*, a quantity of air suitable for the treatment to be effected.

During the working of the furnace, the fan being in operation, the hopper is thus converted into a chamber for the combustion of the fumes liberated by the ore or of the volatilized metals, thereby enabling the furnace to be utilized as a combustion and enriching chamber.

What I claim is:

1. An electric furnace for treating ores, comprising a rectangular vat, a charging hopper above the vat, inclined electrodes on each side of the hopper and extending into the vat the number of the said electrodes being determined by the length of the said vat, and a return electrode forming part of the earth of the furnace, and arranged directly below the hopper.

2. An electric furnace for treating ores, comprising a rectangular vat, a charging hopper above the vat, inclined electrodes on each side of the hopper and extending into the vat, the number of the said electrodes being determined by the length of the said vat, the said electrodes surrounded each by a water-jacket, being arranged close to both the hopper and the wall of the vat, thus taking off any vault, and a return electrode forming part of the hearth of the furnace, and arranged directly below the hopper.

3. An electric furnace for treating ores, comprising a vat having an electrode at its bottom, a charging hopper arranged above the vat directly over the said electrode, said hopper being provided at its base with openings in two of its sides and with a large opening in one side adjacent its upper end, and electrodes on each side of the hopper and extending into the vat.

In testimony whereof I have hereunto set my hand at Paris this 26th day of July 1920.

AGAMEMNON COUNAS.
